UNITED STATES PATENT OFFICE.

WILLIAM V. DERBY, OF BALTIMORE, MARYLAND, ASSIGNOR TO THE CROWN CORK AND SEAL COMPANY OF BALTIMORE CITY, OF BALTIMORE, MARYLAND, A CORPORATION OF MARYLAND.

CAPPING APPARATUS.

Application filed October 16, 1920. Serial No. 417,362.

To all whom it may concern:

Be it known that I, WILLIAM V. DERBY, a citizen of the United States, residing at Baltimore, and State of Maryland, have invented certain new and useful Improvements in Capping Apparatus, fully described and represented in the following specification and the accompanying drawings, forming a part of the same.

10 This invention relates to capping apparatus.

It is the principal object of the invention to provide a capping apparatus such that crowns or other caps are properly positioned 15 in the capping heads, and such that the apparatus is readily adapted for use with capping heads moving past the crown supply chute in one direction or the other.

With this general object in view, the invention consists in the combinations, details of construction and arrangement of parts which will first be described in connection with the accompanying drawings and then more particularly pointed out.

25 In the drawings,

Fig. 1 is a view in horizontal cross-section, with parts in plan, of a capping apparatus constructed in accordance with the invention;

30 Fig. 2 is a vertical sectional view through the crown chute and one of the capping heads;

Fig. 3 is a view, partly in side elevation and partly in section, with parts removed;

35 Fig. 4 is a cross-sectional view taken on the line 4—4 of Fig. 3;

Fig. 5 is a similar view taken on the line 5—5 of Fig. 4;

Fig. 6 is a detail view showing in end 40 elevation the wiping latch removed; and

Fig. 7 is a view, in side elevation, with parts in section, of one of the crown wipers and its mounting.

45 Referring to the drawings, which illustrate an embodiment of the invention, a plurality of capping heads 11 are connected in any suitable manner with a central shaft 12. Upon rotation of shaft 12 the capping heads have an orbital movement past a crown feeding chute 13. This chute communicates with a hopper or other suitable source of crown supply (not shown). Each capping head in the present embodiment, in-

cludes a throat ring or capping die 15. Below each capping die is a crown platform 16 having an open sided chamber 17. These chamber openings register with the chute 13 as the capping heads move past the latter, so that crowns sliding down the chute by gravity may enter the crown platforms. It sometimes happens, however, that gravity is not sufficient to properly position the crowns in the platform chambers.

There is provided means for positively acting on the crowns to wipe them into 55 centered position in the crown platforms of the capping heads. Although capable of various constructions, in the embodiment here illustrated, mounted as hereinafter described, is a crown guiding and wiping 60 latch 19. The side wall 20 of the chute is cut away, as appears in Fig. 1, to receive the head of this wiper 19. The latter is provided with a guiding face 21 substantially 65 parallel with the chute and forming, in effect, a continuation of the chute wall 20. The wiping latch also has a crown wiping 70 face 22 oblique to the chute. As indicated by the dotted lines in Fig. 1, these crown 75 engaging faces are offset to allow for the skirt of the crown, and the corners are rounded as shown to prevent crowns from catching thereon.

Means is provided for yieldingly mounting the wiper 19, and in structures embodying the invention to the best advantage, the wiper is pivoted and has a pinion meshing with a spring pressed member, for example, a rack. Although capable of various constructions, in the present embodiment a 80 support or frame piece 25 carries a housing 85 26 which may conveniently be cast integral therewith. The housing 26 is open at the bottom and inserted therein is a pinion 27. This pinion is freely mounted on a stud bolt 28 which extends through the housing and is held in place by a nut 128. The end of wiper 19 is pivotally mounted on this stud 28 and has a tongue and groove connection with the pinion 27, pinion and wiper being held together by the head 228 of the stud bolt 28. The wiper is thus pivotally mounted to swing in a horizontal plane.

In order that the wiping latch may be yieldingly held in normal position, as here 100 shown as an example, the pinion 27 meshes

with rack teeth 29 formed on a cylindrical rack member 30. The rack 30 is slideable in a cylindrical housing 31 which is conveniently integral with housing 26, having 5 one end open, as appears in Fig. 1, for the reception of the rack. The rack 30 is closed at its outer end and open at its inner or telescoped end. Within the rack member 30 is a spring 32 which bears against the 10 closed end of housing 31.

As the crowns slide down chute 13, they tend to enter the crown platforms as the latter move past the end of the chute. Should a crown fail to take its proper position in the platform, it will, as the head moves on, engage the face 22 of the wiping latch 19. Due to this engagement, the crown is positively wiped into proper position in the platform. Should a defective crown or 15 the like become jammed between the wiping latch and the capping head, the latch can yield. The excess pressure overcomes the force of spring 32 and the wiping latch swings on its pivot, the rotation of pinion 20 27 forcing back rack 30 against its spring. This yielding of the wiping latch releases the jammed crown. Upon release of the jammed crown, the spring forces rack member 30 forwardly again, thus rotating pinion 25 30 in the reverse direction to return the wiping latch 19 to normal position.

Means is provided for fixing this normal position. As here shown, as an example, the wiping latch 19 has a heel 33 which engages 35 the end of a stop screw 34 threaded through part of frame 25 and adjustably set by a lock nut 35. This engagement of heel 33 with stop 34 limits the movement of the wiping latch under force of spring 32.

40 The drawings show a wiping latch located for use with clockwise rotation of the capping head, as indicated by the arrow in Fig. 1. It is sometimes desired to reverse the direction of rotation, and means is provided for mounting the wiping latch for 45 service on either side of the chute. As here shown, as an example, on the right hand side of chute 13 (as viewed in Fig. 1) is a frame piece or support 38 that is like frame piece 25, except that it is oppositely disposed. On the frame 38 are housings 39 and 40 which are reversed counterparts of housings 26 and 31, the two sets of housings being symmetrically located with respect to the chute. 50 Housing 39 is provided with a bore 41 to receive the stud bolt 28 and the frame piece 38 has a bore 42 to receive the stop screw 34. When the direction of rotation is changed, a reverse counterpart of the wiping latch 19 is provided. This wiper, together with pinion 27 and bolt 28 are mounted in the housing 39. Rack 30 and spring 32 are transferred to housing 40 and stop-screw 34 is transferred to bore 42.

65 It sometimes happens that the vibration

of the machine dislodges a crown from its position in the crown platform as the platform travels from the chute to the point where the capping operation takes place. This vibration also sometimes dislodges a 70 crown to which no bottle has been presented. There is provided a crown wiper located a substantial distance beyond the chute for positioning crowns just prior to the capping operation, and a crown wiper located in 75 advance of the chute for positioning crowns that may be carried around without being applied to a bottle.

While variable within a wide range, in structures embodying the invention to the best advantage, 80 these two crown wipers are functionally interchangeable. This may be accomplished, for example, by providing two crown wipers having convex crown engaging faces and locating these wipers symmetrically with respect to the chute.

Although capable of various constructions, in that here shown as an example, mounted, as hereinafter described, on the left hand side of the chute (looking at Fig. 1) is a crown wiper 85 in the form of a long curved bar 45. This bar has a convex crown-engaging face 46 which is substantially tangential to centered crowns, as appears clearly in Fig. 1.

As the capping heads move onwards away from the chute, any dislodged crown will engage the curved face 46 of the wiper 45 and by such engagement will be wiped into centered position. The wiper 45 is located far enough beyond the chute to insure the crowns being centered just prior to the point where the bottles are presented in the capping operation.

Means is provided for yieldingly mounting the wiper 45 and in structures embodying the invention to the best advantage the wiper is pivoted and has a pinion meshing with a spring pressed member.

Although capable of various constructions, the mounting may conveniently duplicate the mounting for wiper latch 19, thereby reducing the number of different parts to be manufactured. Such a construction is shown in the present embodiment. The frame piece 25 has a pinion housing 47 and a rack housing 48, which are like the housings already described.

In the former is a pinion 49 mounted on a stud bolt 50 and having a tongue and groove connection with the wiper 45. Pinion 49 meshes with a cylindrical rack 51

slidable in the housing 48 and pressed forward by a spring 52. To fix the normal position of the wiper a heel 53 on the latter engages a stop screw 54 threaded through frame piece 25 and adjustably set by lock nut 55.

In the construction shown bolt 50, pinion 49, rack 51, spring 52 and stop screw 54 are counterparts of bolt 28, pinion 27, rack 30, spring 32 and screw 34 respectively.

As before stated there is provided a

wiper for positioning dislodged crowns that have been carried around without being attached to a bottle, this wiper being functionally interchangeable with wiper 45. It 5 was also stated that both wipers might have convex crown engaging faces. Although capable of various constructions, this third wiper and its associated parts may conveniently be counterparts of the wiper 45 and 10 its mounting. Such a construction is here shown as an example. Located on the opposite side of the chute from wiper 45 and symmetrically arranged with relation thereto, is a crown wiper 56 comprising a curved 15 bar that is the reverse counterpart of bar 45. The wiper 56 has a convex crown engaging face 57 which, like face 46, is substantially tangential to the edge of a centered crown. Should a crown be carried 20 around with the head and become dislodged, it will be wiped into centered position by its engagement with the wiper face 57. In the present embodiment of the invention, the wiper 56 is mounted by means of parts that 25 are duplicates of the mountings already described. The pinion and rack housings are shown at 58, 59 and it is to be understood that they contain duplicates of pinion 49, rack 51 and spring 52, the pinion being 30 mounted on stud bolt 60. A stop screw 61, duplicating screw 54, fixes the normal position of wiper 56.

Should the direction of rotation of the 35 capping heads be reversed, the wipers 45 and 56 exchange functions. That is, wiper 56 positions crowns just prior to capping, and wiper 45 positions crowns carried around to the starting point.

With the construction described, the 40 crowns are positively positioned at the several points desired by parts that are simple in construction and operation, economical to manufacture and easy to assemble.

It is to be understood that in the description 45 and claims the word "crown" is used as an exemplification and that the invention is not limited to that particular type of cap.

What is claimed is:

1. In a capping apparatus, the combination 50 with a crown feeding chute and a plurality of capping heads arranged to move past said chute and provided with crown-receiving platforms, of a pivotally mounted wiper for wiping crowns into position in said platforms, a pinion associated with said wiper, a toothed member meshing with said pinion, and a spring tending to hold the wiper in normal position.

2. In a capping apparatus, the combination 60 with a crown feeding chute and a plurality of capping heads arranged to move past said chute and provided with crown-receiving platforms, of a pivotally mounted wiper for wiping crowns into position in said platforms, a pinion associated with said

wiper, a rack meshing with said pinion, and a spring tending to hold the wiper in normal position.

3. In a capping apparatus, the combination 70 with a crown feeding chute and a plurality of capping heads arranged to move past said chute and provided with crown-receiving platforms, of a pivotally mounted wiper for wiping crowns into position in said platforms, a pinion associated with said wiper, a rack meshing with said pinion, a housing in which said rack is slidable, and a spring between said rack and said housing.

4. In a capping apparatus, the combination 75 with a crown feeding chute and a plurality of capping heads arranged to move past said chute and provided with crown-receiving platforms, of a pivotally mounted wiper for wiping crowns into position in said platforms, a pinion associated with said wiper, a toothed member meshing with said pinion, a spring tending to move the wiper toward normal position, and a stop for limiting the movement of the wiper under the 80 force of said spring.

5. In a capping apparatus, the combination 85 with a crown feeding chute and a plurality of capping heads arranged to move past said chute and provided with crown-receiving platforms, of a pivotally mounted wiper for wiping crowns into position in said platforms, a pinion associated with said wiper, a toothed member meshing with said pinion, a spring tending to move the wiper toward normal position, and an adjustable 90 stop for limiting movement of the wiper under the force of said spring.

6. In a capping apparatus, the combination 95 with a crown feeding chute and a plurality of capping heads arranged to move past said chute and provided with crown-receiving platforms, of a wiper for wiping crowns into position in said platforms, a stud on which said wiper is pivotally mounted, a pinion mounted on said stud and having a tongue and groove connection with said wiper, a rack meshing with said pinion, and a spring tending to move the wiper into normal position.

7. In a capping apparatus, and in combination, a crown feeding chute, a plurality of capping heads arranged to have an orbital movement past said chute and provided with crown-receiving platforms, a crown-wiper adjacent the chute mouth, and two crown-wipers symmetrically arranged on either side of the chute mouth and spaced therefrom.

8. In a capping apparatus, the combination 125 with a crown feeding chute and a plurality of capping heads arranged to move past said chute and provided with crown-receiving platforms, of a wiper located adjacent the chute for wiping crowns into posi- 130

tion in the platforms as the latter move past the chute, means for mounting said wiper to yield to release a jammed crown, and two wipers located on opposite sides of said chute and spaced therefrom, one for wiping crowns into position in the platforms just prior to the capping operation, and the other for wiping crowns into position that are carried around without being applied to a bottle.

9. In a capping apparatus, and in combination, a crown-feeding chute, a plurality of capping heads arranged to move past said chute in either clockwise or counter-clockwise direction and provided with crown receiving platforms, means for mounting a crown wiping latch on either side of said chute, and two crown wipers located on opposite sides of the chute and spaced therefrom and capacitated to act interchangeably to wipe crowns into position in the platforms just prior to the capping operation and to wipe crowns into position that are

carried around without being applied to a bottle, depending on the direction of rotation of the capping heads.

10. In a capping apparatus, and in combination, a crown feeding chute, a plurality of capping heads arranged to have an orbital movement past said chute and provided with crown-receiving platforms, a crown wiper adjacent the chute mouth, and two convex crown wipers symmetrically arranged on either side of the chute mouth and spaced therefrom.

11. In a capping apparatus, and in combination, a crown feeding chute, a support on each side of the chute, each support having a bearing for a wiper pivot adjacent the chute mouth, and a bearing for a wiper pivot spaced from the chute mouth, said bearings being symmetrically arranged with respect to the chute.

In testimony whereof, I have hereunto set my hand.

WILLIAM V. DERBY.
